UNITED STATES PATENT OFFICE.

FREDRICH P. KRINGS, OF CHICAGO, ILLINOIS, ASSIGNOR OF ONE-HALF
TO WILLIAM H. FLETCHER, OF SAME PLACE.

LOCK.

SPECIFICATION forming part of Letters Patent No. 289,542, dated December 4, 1883.

Application filed May 22, 1883. (Model.)

To all whom it may concern:

Be it known that I, FREDRICH P. KRINGS, of Chicago, county of Cook, and State of Illinois, have invented certain new and useful 5 Improvements in a Door-Lock, of which the following is a full, clear, and exact description, that will enable others to make and use the same, reference being had to the accompanying drawings, and to letters of reference marked 10 thereon, forming a part of this specification.

This invention relates to improvements in door-locks; and it consists of certain novel features in the construction and arrangement of the parts, as will be hereinafter more fully set 15 forth in detail in the specification, and pointed out in the claim.

Figure 1 is a side elevation, the cap-plate being removed to show the interior of the lock, the door and jamb-post being in section. Fig. 20 2 is a horizontal transverse section in the plane 2 2, Fig. 1; Fig. 3, a vertical section in the plane 3 3, Fig. 1, looking in the direction indicated by the arrows; Fig. 4, a face view of the keeper or striking plate.

25 Referring to the drawings, A represents the door; A', the case or box inclosing and retaining the lock mechanism; A², the keeper or striking plate, and A³ the face-plate, attached to and forming a part of the case A'. The recess

30 A⁴, for the reception of the lock, is cut out from the front edge of the door, and is secured in place by the face-plate A³, attached to the door by the screws A⁵ A⁵, and to the lock-case by the screws A⁶ A⁶, as shown in Fig. 1 of the 35 drawings. The keeper A² is provided with the usual apertures, and the jamb-post B' with recesses corresponding thereto, for the reception of the latch-bolt B and the locking-bolt C. The inner end of the latch-bolt passes

40 through an aperture in the outer end of the rectangular sliding frame a, and is secured in relation thereto by the pin a'. By this arrangement the latch-bolt is adapted to move simultaneously with the frame a, or may be 45 forced back independent of the frame a. The frame a is adapted to have an endwise adjustment, and is forced backward by the longitudinal movement of the spindle B², provided with the triangular projection B³, the bearing-surface of which is slightly curved, and by fric-

tional contact of the same with the beveled lug a², formed integral with the frame a, the latch-bolt is released from engagement with the keeper. The lug a² projects laterally from and a little beyond the plane of the frame a, through 55 which the spindle B² passes. This spindle is not susceptible of a rotary movement, but only an endwise adjustment. The latch-bolt is drawn back by pulling on the handle B⁴, or by pushing in on the knob B⁵, as the case may be. 60 The latch-bolt is automatically thrown out by means of the spring a³, coiled around the post a⁴, one end of the spring bearing against the head of the latch-bolt, while the other end rests against the inside of the case, as shown 65 in Fig. 1 of the drawings. The frame a is prevented from moving too far in the direction of the latch-bolt by means of the shoulders a⁵ a⁶ coming in contact with the stops a⁷ a⁸. The locking-bolt C is cut away back from the 70 head C', so as to provide room for the four tumblers b b' b² b³, placed on the front side of the cut-away part of the bolt, and to bring it on a level with the head of the bolt. The back parts of the series of tumblers are provided with 75 the irregular slots C², the transverse parts of which are slightly curved to allow the tumblers to have a corresponding lateral movement, while the rectangular parts of the slots extending backward provide for a longitudinal movement of the bolt independent of the tumblers. The ends of the tumblers are retained in proper 80 relation to the locking-bolt by means of the rectangular post C³, attached to the bolt. The lower edges of these parts of the tumblers are 85 cut away in different curved planes, so that a key of a particular shape is required in order to bring the tumblers into the right position for moving the bolt.

Each of the series of tumblers has an independent lateral movement relative to the others. The opposite ends of the series of tumblers are rounded and perforated to engage with the pivot-post C⁴, which is rigidly attached to the back of the lock-case, and projects through 95 the elongated slot C⁵ in the locking-bolt, so as to permit of a longitudinal adjustment of the same. Each tumbler is provided with a spring, C⁶, arranged in the same plane therewith, one end of said spring being secured to the tum- 100

bler, while the opposite end has a bearing against and is retained in place by the post D. These springs serve to automatically throw the back ends of the tumblers down, so that the 5 offset made by the widest part of the slot C² engages with the post C³, and thereby prevents all possibility of the bolt being forced out of the locking position, (shown in Fig. 1,) except by the use of the proper key, thus avoiding 10 the danger of having the bolt sprung back by inserting an instrument into the door-jamb. The bolt C cannot be thrown into a locking position by means of a key, but is automatically forced out into engagement with the keeper by 15 means of the spring C¹, coiled around the post C³. The inner end of the trigger D' is secured to the post D², and is adapted to have a pivotal movement from this point. The opposite end of the trigger projects a little beyond the face- 20 plate, attaching the lock to the door, and engages with the beveled slot D³ in the keeper-plate. (Shown in Fig. 4 of the drawings.) The upper side of the trigger is provided with the upward-projecting post d, which is adapted to 25 engage with a corresponding aperture, d', in the under side of the head of the locking-bolt, which serves to retain the bolt in an unlocked position against the pressure of the spring C¹ when the door to which the lock is attached 30 is open. Now, in closing the door, the outer projecting end of the trigger is forced downward by reason of coming in contact with the beveled line d² on the keeper, (shown in Fig. 4 of the drawings,) which movement has the 35 effect of releasing the locking-post d from engagement with the under side of the locking-bolt, which is then thrown out into a locking position by the spring C¹. The trigger is automatically thrown into engagement with the 40 locking-bolt by means of the spring b⁴. Above the locking-bolt is placed the lever-catch D⁴, which has an axial bearing near its longitudinal center on the post D. The front end of

this catch is rounded, as shown in Fig. 1, and is retained in the two positions to which it is 45 capable of being adjusted by the bow-spring d⁵. The piece d⁶ is set on the outer side of the lever-catch, and is a prolongation of the same, and extends out flush with the surface of the 50 face-plate, through an elongated aperture in the same, which admits of this end of the catch being thrown up or down, as may be required, and imparts a corresponding movement to the opposite or inner end. The object of this lever-catch is to engage with the locking-bolt 55 and prevent the same from being thrown into a locking position when the door is closed and the trigger thrown out of engagement with the locking-bolt. This is done by tipping up the outer end of the catch, which throws down the 60 inner end and engages it with the notch d⁶ in the upper edge of the locking-bolt, which securely holds the bolt in an unlocked position and permits of the door being closed without locking the same. By simply throwing the 65 outer end of the catch D⁴ down the opposite end is released from contact with the locking-bolt, and the operation of automatically locking the door by closing the same is the same as before described. 70

Having thus described my invention, what I claim as new, and desire to secure by Letters Patent, is—

The combination, with the locking-bolt C, having the aperture d', of the spring C¹, the 75 trigger D', provided with the upward-projecting post d, the post D², the spring b⁴, and the keeper A², provided with beveled slot D³, whereby said bolt is automatically thrown into a locking position by the closing of the door, 80 substantially as described.

FREDRICH P. KRINGS.
